United States Patent Office

Des. 211,434
Patented June 11, 1968

211,434

BABY'S FEEDER

David Atkin, London, England, assignor to The Cannon Rubber Manufacturers Limited, London, England

Filed Dec. 8, 1966, Ser. No. 4,969

Claims priority, application Great Britain July 14, 1966

Term of patent 14 years

(Cl. D83—8)

Fig. 1.

Fig. 2.

Fig. 3.

Fig. 4.

Fig. 5.

FIG. 1 is a perspective view of a baby feeder showing my new design;

FIG. 2 is a cross-section taken on line 2—2 of FIG. 3;

FIG. 3 is a front elevation of the feeder in an alternate position;

FIG. 4 is a front elevation partially shown in cross-section; and

FIG. 5 is a top plan view thereof.

I claim:

The ornamental design for a baby's feeder, substantially as shown.
